UNITED STATES PATENT OFFICE.

HORATIO W. SOUTHWORTH, OF SPRINGFIELD, MASSACHUSETTS.

ELECTRIC SIGNALING APPARATUS.

SPECIFICATION forming part of Letters Patent No. 267,945, dated November 21, 1882.

Application filed June 12, 1882. (No model.)

To all whom it may concern:

Be it known that I, HORATIO W. SOUTHWORTH, a citizen of the United States, residing at Springfield, in the county of Hampden and State of Massachusetts, have invented new and useful Improvements in Electric Signaling Apparatus, of which the following is a specification.

This invention relates to improvements in apparatus for transmitting electric signals in which are employed magnetic needles or bars, which are caused to be deflected by sending an electric current through a coil surrounding said needle or bar; and it consists in improved means for governing the vibratory movements of the needle, for establishing by means of the motion of said needle more positive signaling-connections at the stations, for increasing the effectiveness of this class of signaling apparatus, and for governing the needle-deflecting current to cause a simultaneous and equal deflection of all the needles on one circuit.

In the drawings forming part of this specification, Figure 1 is a plan view of an electric signaling apparatus, together with its connecting-wires, adapted to the requirements of a main station, embodying my improvements. Fig. 2 is a view of one of said instruments adapted to the requirements of a way-station. Fig. 3 illustrates the above-mentioned instruments, together with their several connections, when they are located one at a central or main station and the other at a way-station. Fig. 4 illustrates the arrangement of the commutator and directly-connected devices relative to the table and the magnetic bar.

This invention is in the nature of an improvement upon that shown and described in my United States Patent of August 8, 1882, No. 262,252, to which reference may be had.

A is the table of the instrument. D is the base thereof. B is the coil, surrounding the magnet-bar. C is a permanent magnet. D is a pivoted magnetic bar. E is an arm on bar D. E² is a pendulous connecting-wire, suspended at one end of the arm E. O O² are combined guards and signaling-connections. F is a rotating commutator-post. I I I I are arms on post F. N² is a commutator-arm on said post. Z Z are contact-arms on arm N². 1 2 3 are con-

tact-pins, 2 being shown in dotted lines on post F. A is a stop-pin in table A. B is a graduator. S is a wire coiled on the graduator B. V indicates pins in said graduator. A² is a graduator-connector. M is a spring-switch. X X' are contact-pins. H is a signal-bell. K is a battery.

The table A is constructed of radial form preferably, and supports on one edge a coil-frame, around which is wound a coil, B, of fine wire. Said coil-frame is constructed with a transverse opening therethrough, and in the lower side thereof is set a proper vertical pivot, upon which is adjusted, in the usual manner, the oscillating or vibrating magnetic bar d, to which is secured, at right angles thereto, the arm e, having hung on the end thereof the freely-swinging pendulous metallic connecting-wire e². On the top of said coil B is secured the permanent magnet c for the purpose of determining the direction N S more strongly than the magnetic force of the earth alone will do. Consequently the movements of the magnetic bar d are more prompt.

The table A is provided (that of the instrument of the central office) with two series of graduation marks and numbers each side of a central point on its border, while the instrument of the way-station is provided with one series only, and the end of arm e carrying the connecting-wire e² swings back and forth over said table and said graduation-marks thereon.

For the purpose of providing suitable means to co-operate with the vibratory arm e and the pendulous wire e² thereon, whereby said arm shall be caused to stop at certain points over the face of table A, and thereby effect such an electric connection as will ring a bell or operate other signals, the wires o and o² are secured in an insulated position in said table, projecting above the surface thereof, having their upper ends bent at right angles thereto, and forming an opening therebetween of V-shape, which at its narrowest part is of less width than the diameter of said pendulous wire e². The outer one of said wires, o, has a longer arm than the inside one, o², and is curved outwardly; but the end thereof is bent inward past the point over table A, at which the end of wire o² stands. The said point of wire o² is located about on the circumferential line described by

the pendulous wire e^2 when arm e swings over table A, while, as above stated, the end of wire o is inside of that line. One of said wires is, as shown, connected with the battery K, and one with the alarm-bell h , or other suitable signal device, or for forming a connection for utilizing a local current, and a wire from said bell connects it with the opposite pole of said battery. Said two wires in the central-office instrument 5 are located beyond the aforesaid graduating marks and numbers, near to said coil-frame; and when table A is provided with duplicate series of said marks and numbers said wires o o^2 are duplicated on the table, as shown in Fig. 1, and the connections of both pairs thereof with the bell and the battery are common.

A spring-switch, m , is secured to a connection-post, m^2 , on the base D, and is adapted to spring against a connection post, x , there resting until it is swung away from it against the post x' .

For the purpose of better controlling the force of the electric current which actuates the instruments on a circuit, a graduator, b , is connected with the central-office instrument, consisting of a coil of fine wire, s , wound spirally around a cylinder, and at each turn wound around one of pins v therein. Along each side of said pins are fixed two strips, v' , to form a groove therebetween, as shown in Fig. 1. Only one end of wire s on said graduator is permanently connected with the instrument, and that is attached to a wire, 10, leading from battery K to post x .

35 A portable graduator-connector, a^2 , is connected by a suitable wire to a wire, 11, running from the opposite pole of battery K to that with which wire s is connected. Said connector a^2 consists of a handle of insulating material, having fixed in it a metallic support for a metallic wheel, r , the wire connecting said connector with said wire 10 being connected with the metallic support of said wheel.

The connecting-wires o o^2 located on table 45 A of the instruments are, in those of the outlying stations, fixed at the number on said table which corresponds with the numbers of the stations.

The several connections of instruments, 50 alarm-bell, battery, commutator, and switch are clearly shown in the drawings, and will be easily understood by one skilled in the art.

For the purpose of changing the direction of the current through the coils B of the instrument, whereby the arm e , carried by the magnetic bar d , may be caused to vibrate either to the right or to the left for the purpose of establishing connections upon lines running out from either side of the instrument, an ordinary commutator is established under table A, which is operated by the rotating post f , as clearly shown in Fig. 4. The arms i on said post f serve, when arm e is adapted to vibrate in both directions over table A, to restrain the 55 said vibrations so that they shall be in the desired direction only by turning said post so

that one of said arms acts as a stop to arm e at the center of said table. The arms n on post f strike a pin set in table A and determine the degree of rotation of said post when 70 turned for the above purpose.

The instruments at the outlying stations are provided with a permanent stop-pin set in table A about in the position of post f , so that arm e may be caused to vibrate only between 75 said stop-pin and the side of said coil-frame, moving over said numbers and said wires o o^2 .

Referring to Fig. 1, wire 10 connects battery K and coil B through the commutator f and post x and wire 13. Wire 11 connects the opposite pole of the battery through said commutator with post x' and a branch, 12, through an intermediate connection with 11, connects bell h with the battery. A branch, 14, from wire 10 connects the wire o^2 on table A with 85 the battery. Wire 15 connects arm o , likewise on table A, with the bell h . Wire 13 connects coil B with post x , and through switch m with the line-wire 17. Line-wire 16 is connected directly with coil B. In operating from central station swinging switch m from post x to x' (the lines 16 and 17 being connected simply or through a way-station instrument) causes the current to circulate from the battery outward through wire 10, coil B, and line 16, and 90 inward through line 17, switch m , and wire 11, back to battery. The contact of the pendulous wire e^2 with the arms of the wires o o^2 closes a circuit from battery through wires 14, 15, 12, and 11, in which bell h is connected. The outlying instruments, being connected in lines 16 95 and 17, and being subject to like electrical influence with the central-station instrument, their arms e on the magnetic bars d follow the movements of the bar d at the central station. When switch m at a way-station, Fig. 3, is carried into contact with x' a current is established from the battery K', through wire 11', post x' , switch m , and line 16, and by the latter through coil B of the central station by 100 wire 13 to post x , and thence through wires 17 and 10 to the battery, whereby bar d at the last-named station is deflected. Said battery K', Fig. 3, is a local battery of the way-station.

115 The operation of the above-described devices is as follows: To call from an outlying station, the switch m of that station is swung from post x to x' , establishing a current through all of the coils B in the circuit. The said current in its 120 full strength will throw out all the bars d in the circuit to their utmost limit. The central-office instrument, having its wires o o^2 located as above described and shown, will thus have its alarm-bell connection established by the dropping of the pendulous wire e^2 on arm e between the said wires as said arm begins its retrograde movement, while the bars of all the outlying stations, as soon as the current is broken by the calling station, will drop back without making 125 any connections with wires o o^2 , because said pendulous wire, as bar e swings back, will strike 130

the curved end of wire o , which guards the point of wire o^2 , and be carried outside of the former, and thus be prevented from being caught between said wires so as to form a connection. Supposing, now, that the central office is requested to call station 11, it moves switch m to post x' , inserting at the same time the graduator-connector wheel r between the strips v' and against the ends of the pins v , in the graduator. This offers a side connection to the current, and in proportion as its resistance is increased the current through this side connection will become diminished, and thereby the current through the main line be strengthened more and more. By giving at the start little resistance to the graduator, almost the full current will take its way through the side connection, and but very little will pass through the line. The magnetic bars d will in consequence be deflected very slightly at the commencement. If, now, the resistance in the graduator be increased, the current in the main line will increase, and slowly the bars d will be deflected more and more. All the bars in the circuit will move alike. As soon as the bar of the central office has passed No. 11 on table A, the bar at station 11 has gone beyond the end of the wire o^2 thereat, and the central office operator now interrupts the current, and all the bars d in the circuit will fall back, except that at station 11, whose pendulous wire will drop between said wires o o^2 . Thus the local battery of station 11 becomes connected with the bell h , and that bell only on the circuit will ring. To remove said pendulous wire from between the wires o o^2 it is only required to give a full current to the line by switch at main office, when arm e will swing away from said wires and then drop back, carrying wire e^2 outside of wire o , as above described.

What I claim as my invention is—

1. The combination of a series of instruments in circuit, each having an electric signaling apparatus, magnetic bar d supporting the arm e , to which is suspended the wire e^2 , and the separated connection-wires o o^2 , set in different positions in the different instruments, coil B, magnet c, and means, substantially as described, for sending an electric current through all of said coils simultaneously, substantially as described.

2. The combination of a series of instruments in a circuit, each having an electric signaling apparatus, magnetic bar d , supporting arm e , to which is suspended the wire e^2 , the wires o o^2 , coil B, magnet c, a graduator, b, and connector a^2 , adapted to be attached to one of said instruments, said wires o o^2 being set at different positions in the different instruments, and means, substantially as described, for sending an electric current through all of said coils simultaneously, substantially as set forth.

3. The combination, in an electric signaling apparatus, of an alarm-bell of the magnetic bar d , supporting the arm e , and having the wire e^2 suspended thereto, of the wires o o^2 , connected with said bell and a battery, coil B, magnet c, and means, substantially as described, for sending an electric current through said coil, substantially as described.

HORATIO W. SOUTHWORTH.
